CONTROL MECHANISM FOR SOUND REPRODUCING

Fred Van Eps, Plainfield, N. J.

Application February 22, 1944, Serial No. 523,384

10 Claims.

(Cl. 274—1)

1

The invention relates to a control mechanism or control device for sound reproducing apparatus for phonograph records and the like and more particularly to a control mechanism for sound reproducing means having a turntable associated therewith and by means of which selected portions of the sound record may be played or deleted at will.

In the use of phonographs and other sound reproducing apparatus it is often desirable to stop the reproduction at a precise point of the sound track for the purpose of copying, recording or broadcasting of selected portions of the records. Heretofore, this has been accomplished by disengaging the pickup mechanism from the sound track at the selected point and then again bringing it into engagement with the other portions of the record to be played or reproduced.

It has been found very difficult to make accurate reproductions or deletions with this type of arrangement for the reason that it is almost impossible to reengage the jewel point at the precise point of the sound track once it has been raised from the record. This can readily be understood from the fact that the average commercial record usually has 120 to 150 grooves to an inch. Thus the replacement of the point of necessity becomes somewhat haphazard, and if the record is kept revolving with the turntable, accurate reproduction or deletions becomes next to impossible. On the other hand, if the record is stopped from revolving together with the turntable, a swishing sound will be heard when the turntable is again started for the reason that it takes at least one revolution to build up proper reproduction speed.

For this and other reasons it has been found impractical to do any copying or recording by using this type of control mechanism.

It is, therefore, among the objects of the present invention to provide a control device by means of which the reproduction may be stopped instantaneously at any point of the sound track without disengaging the point of stylus from the sound grooves.

Another object is to provide a stop device for the record without stopping the rotation of the turntable.

A further general object is to provide a device of the character described which will perform efficiently the purpose for which it is intended; which is simple and economical of construction; which can be manipulated expeditiously, conveniently and safely with accuracy and which easily

2

can be assembled and installed on a conventional sound reproducing apparatus.

Other objects and advantages inherent in the invention will become apparent from the following description and accompanying drawing which disclose by way of example an embodiment of the invention.

In the drawing:

10 Figure 1 is a top plan view of a phonograph table showing the device of the invention mounted thereon.

Figure 2 is a fragmentary top plan view of the device drawn to an enlarged scale.

15 Figure 3 is a section taken along the line 3—3 of Figure 2, and

Figure 4 is a section taken along the line 4—4 of Figure 2.

20 Referring in greater detail to the drawing, the phonograph table or base 10 is provided with a conventional felt covered rotatable turntable 11, which supports a disc record 12.

Pivotedly mounted on the table 10 is the playing arm or tone arm 13 having at its free end a pickup mechanism 14.

25 The turntable is provided with a central pivot 15 over which the record 12 fits. The rotation of the table is accomplished by a motor or spring not shown in the drawing.

The pickup mechanism is of the usual well-known construction and will not be described in detail herein. Operative engagement of the pickup mechanism with the sound track of the record is brought about by a needle or stylus of the conventional type (not shown in the drawing).

35 The stop device or control mechanism according to the invention comprises a plate 16 of steel or other magnetic material which is provided with a hub 17 fitting over the pivot 15 of the turntable 11. One side of the plate is provided with 40 a frictional covering 16a, such as rubber, for engaging the ungrooved portion of the record 12.

This frictional covering should provide sufficient frictional connection between the disc 16, when arrested, and the record 12 to overcome the frictional drive connection between the turntable 11 and the record 12.

45 In this connection it might be remarked parenthetically that the conventional record has a central ungrooved portion which usually bears the title of the record and the manufacturer's identifying trade-mark or symbol.

It will be understood that due to the frictional contact between the record 12 and the plate 16, the latter normally will rotate with the record 55 and the turntable.

Supported in gimbals mounting comprising the pair of frames 18 and 19 are the electro-magnets 20. The frame 18, which carries the electro-magnets, is pivotally mounted within the frame 19 at 21 whereas the frame 19 is pivoted within the fork 22 at 23. The fork 22 is in turn pivotally connected to the vertical shaft 24 of the supporting arm 25. In this manner a universal articulation is provided for the electro-magnet 20 so that they can adjust themselves to any defects or wobbling of the record.

The supporting arm 25 is pivotally mounted on a horizontal fulcrum pin 26 which extends through the vertical shaft 27 and which in turn is mounted on the phonograph table by means of the plate 28.

Conventional clamping bolts 29 and 30 may be included to tighten the fork 22 and the supporting arm 25 about their respective fulcrums.

The electro-magnets are energized from a battery (not shown) through the lead cords 31 which are connected with the terminals 32. A switch (not shown) is used to throw the current on and off for the purpose of energizing and de-energizing the electro-magnets.

The electro-magnets 20 are provided with a pole piece 33 at each side. These pole pieces are barely kept out of direct contact with the plate 16 by means of brass fragments 34 mounted at one side of each pole piece. The brass pieces are so proportioned and adjusted that a gap of about .005 inch will be provided between the pole pieces and the armature plate 16. The brass pieces prevent freezing of the magnets and provide the frictional connection between the disc 16 and the magnets 20.

The hub 17 abuts against the plunger 35 which is mounted in the nipple 36 which in turn is mounted in the fork 22 by means of the bolt 37. The plunger has a reduced portion 38 which projects through the nipple 36 and the intermediate shoulder serves to limit the projection of the plunger by its abutment against the edge of the reduced opening.

The plunger is bored to accommodate the spring 40 which at its other end abuts against the tightening screw 41, which in turn is held in adjusted position by means of the clamping nut 42.

This plunger serves to disengage the armature plate 16 from the pole pieces 33 as soon as the electro-magnets are de-energized by the throwing of the switch. However, the residual magnetism in the pole pieces might still hold the armature plate 16 but for the slight pressure exerted by the plunger 35. Thus the disengagement of the armature plate 16 is instantaneous as soon as the switch is thrown and it will immediately rotate together with the record and the turntable.

When it is desired to reproduce or broadcast a selected portion of the record, the turntable is set in motion and the record disc and the plate 16 are rotated at the regular running speed. As soon as the desired point on the sound track is reached, the switch is thrown resulting in energization of the electro-magnet which causes the armature plate 16 to adhere to the pole pieces and its rotation will be arrested. The friction covering 18 on the bottom of the plate will also cause the disc record to stop while the turntable will continue to rotate at its regular speed. When it is desired to start the record rotating again after the point of the pick-up mechanism has been adjusted, the switch is simply thrown again and the record will instantaneously resume its regular rotating speed with the turntable.

It will be understood that this disclosure is given by way of example and not by way of limitation. The invention may lend itself to a variety of expressions within the scope of the appended claims.

What is claimed is:

1. Control mechanism for the operation of apparatus for reproducing sound from sound records, comprising a rotatable turntable, a record supported and rotated thereby, electro-magnetically controlled means for arresting the rotation of said record without stopping the rotation of said turntable, said means comprising a disc of magnetic material concentric with said record and having a driving connection with the top surface thereof and normally rotating therewith and stationary electro-magnetic means supported on said disc for arresting the rotation of said disc and said record upon the energization of said electro-magnetic means.

2. Control mechanism for the operation of apparatus for reproducing sound from sound records, comprising a rotatable turntable, a record supported and rotated thereby, electro-magnetically controlled means for arresting the rotation of said record without stopping the rotation of said turntable, said means comprising a disc of magnetic material concentric with said record and having a driving connection with the top surface thereof and normally rotating therewith, and a stationary electro-magnetic device mounted above said disc for arresting the rotation of said disc upon energization of said electro-magnetic device and spring urged means for disengaging said magnetic device from said disc upon de-energization of said magnetic device.

3. Control mechanism for sound reproducing apparatus and the like employing a rotatable disc record, comprising a disc of magnetic material for mounting concentrically on the top of the record, said disc having a driving connection with the central top surface portion of the record so that said disc normally will be rotated thereby jointly with said record, and a stationary magnetic device supported on said disc for arresting the rotation of said disc and said record upon the energization of said electro-magnetic device.

4. Control mechanism for sound reproducing apparatus and the like employing a rotatable disc record, comprising a disc of magnetic material for mounting concentrically on the top of the record, said disc having a driving connection with the central top surface portion of the record so that said disc normally will be rotated jointly with said record, a stationary magnetic device mounted above said disc for arresting the rotation of said disc and said record upon its energization, and anti-magnetic means carried by said magnetic device for supporting it on said disc out of direct contact therewith.

5. Control mechanism for sound reproducing apparatus and the like employing a rotatable disc record, comprising a disc of magnetic material for mounting concentrically on the top of the record, said disc having a driving connection with the central top surface portion of the record so that said disc normally will be rotated jointly with said record, a stationary magnetic device mounted above said disc for arresting the rotation of said disc and said record upon its energization, anti-magnetic means carried by said magnetic device for supporting it on said disc out of direct contact therewith, and spring urged means for disengaging said mag-

netic device from said disc upon deenergization of said magnetic device.

6. Control mechanism for sound reproducing apparatus and the like employing a rotatable disc record, comprising a disc of magnetic material for mounting concentrically on the top of the record, said disc having a driving connection with the central top surface portion of the record so that said disc normally will be rotated jointly with said record, a gimbals frame mounted above said disc, an electro-magnetic device supported in said gimbals frame for arresting the rotation of said disc and said record upon energization, and anti-magnetic means carried by said electro-magnetic device for supporting it on said disc out of direct contact therewith.

7. Control mechanism for sound reproducing apparatus and the like employing a rotatable disc record, comprising a disc of magnetic material for mounting concentrically on the top of the record, said disc having a driving connection with the central top surface portion of the record so that said disc normally will be rotated jointly with said record, a gimbals frame mounted above said disc, an electro-magnetic device supported in said gimbals frame for arresting the rotation of said disc and said record upon energization, and spring means carried by said frame for urging said disc away from said electro-magnetic device.

8. Control mechanism for sound reproducing apparatus and the like employing a rotatable disc record, comprising a disc of magnetic material for mounting concentrically on the top of the record, said disc having a driving connection with the central top surface portion of the record so that said disc normally will be rotated jointly with said record, and a stationary magnetic device mounted above said disc upon the energization of said spring urged means for supporting said electro-magnetic device on said disc.

9. Control mechanism for sound reproducing apparatus and the like employing a rotatable disc record, comprising a disc of magnetic material for mounting concentrically on the top of the

record, said disc having a driving connection with the central top surface portion of the record so that said disc normally will be rotated jointly with said record, a gimbals frame mounted above said disc, an electro-magnetic device supported in said gimbals frame for arresting the rotation of said disc upon energization, and spring urged means carried by said frame for supporting said electro-magnetic device on said disc.

10. Control mechanism for the operation of apparatus for reproducing sound from sound records, comprising a rotatable turntable, a disc record frictionally engaging said turntable so as to be rotated thereby, electro-magnetically controlled means for arresting the rotation of said record without stopping the rotation of said turntable, said means comprising a disc of magnetic material concentric with said record having a frictional covering so as to provide sufficient frictional connection between said disc, when arrested, and said record to overcome the frictional drive connection between said turntable and said record.
